UNITED STATES PATENT OFFICE

JOSEPH BEHLE AND HUGO LINNARTZ, OF DALLAS, TEXAS, ASSIGNEES TO THE MURRAY COMPANY, OF DALLAS, TEXAS, A CORPORATION OF TEXAS

PRESS BOX DOOR COUNTERBALANCING DEVICE

Application filed August 13, 1928. Serial No. 299,315.

This invention relates to new and useful improvements in press box door counterbalancing devices.

One object of the invention is to provide a counterbalancing device which will tend to compensate the load when the door is opened and closed, thereby reducing the labor and expediting the operation.

Another object of the invention is to provide a counterbalancing device which is comparatively simple in construction and one which is entirely free from connection with the hinge shaft or trunnion of the door.

A still further object of the invention is to provide a counterbalancing device including a coiled tension spring and a strut member exerting its thrust in the general direction of the longitudinal axis of the spring, whereby a direct downward pull is exerted upon the spring and the strut member is constantly under tension, the advantage of such a structure being that the door in all positions is supported by the counterbalancing device.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is a front elevation of a portion of a press box showing a counterbalancing device constructed in accordance with the invention and applied thereto, and

Fig. 2 is a vertical sectional view of the same.

In the drawings the numeral 10 designates one of the angle members at the lower end of a press box 11, which has the usual side door 12 at its upper end. The side door is hinged at 13 so as to swing outwardly and downwardly as is indicated in dotted lines in Fig. 2.

A bracket 14 is suitably fastened on the angle 10 and the inner end of an arm 15 is pivoted in the bracket. A link or strut 16 has its lower end pivoted to the outer end on the arm 15. The upper end of the strut is piv-

oted in a bracket 17 secured to an angle bar 18 extending transversely of the door 12, preferably below the center thereof.

A stout coiled spring 19 has a hook 20 at its upper end engaged in a hanger 21 secured to the wall of the press box 11. An eye bolt 22 is inserted in one of the apertures 23 of the arm 15 and secured by a nut 24. The eye bolt is connected by a link 25 with the lower end of the spring 19.

The spring is constantly under tension, thus tending to swing the arm 15 upwardly and imparting a longitudinal thrust to the strut 16, whereby the door 12 is held to its closed position. The thrust is somewhat controlled by the location of the bolt 22, as it is obvious that the leverage will be greater when said bolt is located in the aperture 23 furthest from its inner pivot.

It is apparent that the spring 19 will exert an upward pull on the arm 15, thus contributing an upward thrust to the strut 16, which latter is inclined substantially the same as said spring. When the door is swung downwardly the strut 16 will swing the arm 15 downwardly, thus increasing the tension of the spring 19 and counterbalancing the opening movement of the door. This stored energy in the spring will aid in lifting the load of the door when the latter is swung upwardly thus reducing the manual labor. When the door is opened the spring will resist its downward swing thus making for safety and preventing a sudden falling of the door.

The constant tension of the spring and the upward thrust of the strut 16 tending to hold the door in its closed position makes for safety as it will tend to hold the door closed in case it becomes unlatched and also will operate to resist a sudden opening of said door due to the expansion of the compressed bale. It is pointed out that all connection with the hinge shaft or trunnion of the press box door is eliminated and also a fixed and positive connection with the side door is had, thus obviating loose parts and complicated attachments.

It will be noted in Fig. 2 that the press platform 11' is rigidly attached to the side

11 of the press box and is rotated therewith as is common in this art. The strut 16 extends up through a slot 16' in this platform. By this arrangement the spring or the major portion thereof may be located entirely below the platform which not only gets the spring out of the way, but makes for the safety of the men working on the platform in case the spring should break. It also permits the spring to be located within the angle formed by the strut 16 and the arm 15 thus allowing a shorter spring to be used and requiring less travel of the spring than is required of the strut.

15 Various changes in the size and shape of the different parts, as well as modifications and alterations, may be made within the scope of the appended claims.

What we claim is:

- 20 1. In a counterbalancing device for a vertically disposed cotton press box door, a strut pivoted at its upper end to the door above its hinge and extending downwardly below the hinge of the door and below the press platform, an arm pivoted to the lower end of the press box and lying entirely below the press platform and to which the lower end of the strut is pivoted, and a coiled spring lying entirely below the hinge of the door and having its upper end attached to the press box and its lower end attached to the arm and free from connection with the pivotal connection between the strut and the arm.
- 25 2. In a counterbalancing device for a vertically disposed cotton press box door, a strut pivoted at its upper end to the door above its hinge and extending downwardly below the hinge of the door and below the press platform, an arm pivoted to the lower end of the press box and lying entirely below the press platform and to which the lower end of the strut is pivoted, and a coiled spring located entirely below the hinge of the door and lying within the angle formed by the strut and the arm, whereby the extension of the spring is less than the travel of the strut upon fully opening the door.

In testimony whereof we affix our signatures.

JOSEPH BEHLE.
HUGO LINNARTZ.
